UNITED STATES PATENT OFFICE.

LAURENCE E. TOPHAM, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

SPACING MECHANISM.

1,381,256.

Specification of Letters Patent.

Patented June 14, 1921.

Application filed August 23, 1918. Serial No. 251,109.

To all whom it may concern:

Be it known that I, LAURENCE E. TOPHAM, a citizen of the United States, residing at Swampscott, in the county of Essex and State of Massachusetts, have invented certain Improvements in Spacing Mechanisms, of which the following description, in connection with the accompanying drawings, is a specification, like reference characters on the drawings indicating like parts in the several figures.

This invention relates to spacing mechanisms for machines arranged to perform a series of operations upon a piece of work at intervals and to feed the work between successive operations. The invention is herein shown as embodied in an eyeleting machine, but it is equally applicable, for example, to a perforating machine, a lacing hook setting machine or the like.

Machines of this type have for a long time been constructed with spacing mechanisms arranged to be readily adjusted so as to vary the spacing between successive operations. The object of this invention is to provide an improved spacing mechanism whereby the number of parts employed may be reduced and the arrangement in general simplified.

The features of the invention will be best understood from the following description of a preferred embodiment thereof selected for purposes of illustration and shown in the accompanying drawings, in which,—

Figure 1 is a perspective view of the invention applied to an eyeleting machine;

Fig. 2 is a plan view of the same machine;

Figs. 3 and 4 show successive positions of the work-engaging feeding member and its associated spacing mechanism with the spacing lever held in a predetermined position; and

Fig. 5 is a sectional view taken through the fulcrum of the spacing lever.

The invention is herein disclosed as embodied in a machine of the general type shown in Letters Patent of the United States No. 1,205,277, granted November 21, 1916, upon an application of Walter Shaw. In such a machine a frame 10 is provided with a driving shaft 12 on which are mounted a series of cams 14, 16 and 18, the first of which is arranged to reciprocate a lower set 20. Fasteners are supplied to this lower set through a raceway 22 oscillated from the cam 16 into and out of the path of the lower

set and the fastener is set by co-operation with a combined punch and set 24 carried in a lever 26. The combined punch and set constitutes the work engaging feeding member and the arrangement is such that the punch descends and perforates the work and then feeds it laterally to a point where the punch is in alignment with the lower set. The lower set is then elevated to cause the fastener to be delivered to the punched hole and to be set in the work.

The lever 26 is slidably mounted in a support 28 which is pivoted in the frame of the machine and the connection between the lever 26 and support 28 is such as to allow a relative forward and backward movement of the lever and an upward and downward movement of the tool 24 as the lever oscillates upon its pivot 30. As in the patented construction, the forward and backward movement is controlled by a cam 32 arranged to restrict the lateral movement of the tool 24 to a straight line. The support 28 is provided with an extension 34 which constitutes a crank arm by means of which the work-engaging feeding member 24 may be reciprocated laterally. Power for so reciprocating the tool 24 is supplied to the arm 34 from the cam 18 by means of a bell crank lever having an arm 36 engaging the cam and an arm 38 connected to the arm 34 by means of a floating lever 40 and a connecting link 42.

It will be observed that the movement of the arm 38 and its connecting link 42 is necessarily of a fixed magnitude because of its control by the path cam 18. In order for the spacing mechanism to be adjustably effective to feed the work over varying intervals, means are provided for constraining or controlling the path of movement of the floating fulcrum 43 of the lever 40 so that a variable length of movement will be transmitted to the arm 34. In the preferred embodiment these means comprise a U-shaped link 44 pivotally connected by fulcrum pin 43 to an intermediate point of the floating lever 40 and by pin 45 to the rearwardly extending arm of a regulating lever 46. This lever is fulcrumed upon an extension of the fulcrum portion 48 of the bell crank lever 36, 38, and is provided with a trunnion 47 which projects through a bearing in a casing 50 on the frame of the machine. This trunnion and the portion 48

are coaxial. To the upper end of the trunnion there is secured a torsion spring 52, adjustably tensioned by means of a nut 54, and arranged to urge the regulating lever 5 46 to the rear of the spacing plate 56. The latter is provided with a series of holes 10 adapted to receive one or more pins 58 for limiting the movement of the lever 46. The lever 46 may conveniently be connected to 15 a treadle (not shown) by means of a link 60, a bell crank lever 62 and rod 64. Adjustment of the lever 46 will vary the location of the pivot 45 of the link 44.

The effect of changing the location of 15 pivot 45 is to neutralize more or less of the angular movement executed by lever 40 in response to actuation of arm 38. The angular motion of lever 40 is the effective component and the endwise motion is the 20 non-effective component. This mechanism may be considered as comprising a triple linkage 42, 40, 44 of which the middle link 40 is also a lever and has lateral motion of 25 constant amplitude imparted to it by one of the terminal links and has a floating fulcrum guided by the other terminal link so as to neutralize more or less of the angular movement resulting therefrom.

It will be understood that the forward 30 and backward movement of the lever 26 under the control of the cam 32 is contemporaneous with the lateral movement imparted thereto by the spacing mechanism with the result that the work-engaging tool 24 35 moves in a straight line through varying distances and always is brought to a final position in alignment with the set 20. This is so because the distance between the axis of pivot 45 and that of actuating arm 38 40 remains constant.

Successive positions of the parts of the spacing mechanism, shown in Figs. 3 and 4, illustrate what takes place when the work-feeding member moves from an extreme position (Fig. 3) to an intermediate position 45 (Fig. 4) with the regulating lever 46 set for the maximum length of feeding movement. When the lever 46 is moved to the position for a small feeding movement (see Fig. 2), 50 the free end of the link 44 is constrained to move more nearly at right angles to the length of the lever 40, thereby counteracting more of the angular movement of the latter.

Having thus described my invention, what 55 I claim as new and desire to secure by Letters Patent of the United States is:

1. In a machine of the character described, a work-engaging feeding member pivotally supported upon the machine, an actuating lever, a floating lever and simple 60 pivotal connections arranged to transmit motion from the actuating lever to the feeding member, and means for constraining the path of movement of a portion of the floating lever so as to control the amplitude of 65

motion transmitted by the floating lever to the feeding member.

2. In a machine of the character described, a work-engaging feeding member, and means for imparting a feeding movement to said member comprising a power operated lever, a crank for oscillating the feeding member, a connecting link between the power operated lever and the crank, a floating fulcrum for an intermediate point 70 in said connecting link, and means for altering the path of said floating fulcrum so as to vary the extent of feeding motion transmitted by said link.

3. In a machine of the character described, a work-engaging feeding member, means for imparting a feeding movement to said member comprising three serially connected links movable about two adjustably fixed centers upon the frame of the machine, 85 one of said links being fixed to the feeding member, means for imparting movement to the intermediate link, and means for adjusting the relative positions of the fixed centers to vary the feeding movement imparted to 90 the work-engaging feeding member.

4. In a machine of the character described, a work-engaging feeding member, means for supporting said member comprising a pivoted crank arm, power operated 95 means for operating said crank arm comprising an intermediate connecting link, and adjustable means for constraining the path of movement of an intermediate point of said link so as to cause more or less of the angular movement of the link to be imparted to the crank arm and hence to the work-engaging feeding member.

5. In a machine of the character described, a work-engaging feeding member, 105 means for supporting said member comprising a crank arm, a reciprocating actuator, means arranged to transmit motion from said actuator to the crank-arm, the latter said means including pivotally connected links, and adjustable means for constraining the path of movement of an intermediate point in one of said links so as to determine the amplitude of effective motion 110 transmitted to the crank arm.

6. A machine of the character described comprising a work-engaging and feeding member, an operating member, a link connecting said members so as to transmit feeding movement from the latter to the former, 120 an adjustable anchoring pivot, a link arranged to swing on said anchoring pivot and connected to the first said link so as to guide the movement thereof, and means for adjusting said pivot so as to alter the lines of 125 movement of the second link and thereby vary the amplitude of feeding movement transmitted by the first said link.

7. In a machine of the character described, a work-feeding lever, means for 130

- supporting said lever constructed and arranged to allow endwise movement and lateral turning movement thereof, means for constraining the forward and backward movement so as to cause the work-engaging point of said member to traverse a straight line feeding path, and means for imparting lateral movement to the feeding member comprising a power operated lever having a constant amplitude of motion, a link connecting said lever and the supporting means for the feeding member, and means for controlling the path of movement of a portion of said link constructed and arranged to direct more or less of the angular movement of the link to the supporting member so as to cause feeding movement of the feeding lever.
8. In a machine of the character described, a work-feeding lever, an actuating lever arranged to execute angular movement of constant amplitude, a lever arranged to transmit angular movement from the actuating lever to the feeding lever, said transmitting lever being so connected to the feeding lever as to be moved endwise by feeding movement of the feeding lever, and adjust-

able means arranged to constrain the path of movement of a portion of the transmitting lever so as to neutralize various proportions of the angular movement thereof in a way to regulate the extent of angular movement imparted to the feeding lever by the transmitting lever.

9. In a machine of the character described, a work-feeding lever, an actuating lever arranged to execute angular movement of constant amplitude, a lever arranged to transmit angular movement from the actuating lever to the feeding lever, said transmitting lever having three bodily movable pivot members two of which form connection with the actuating lever and the feeding lever respectively, and the third of which constitutes a floating fulcrum, and means for constraining the path of bodily movement of the third pivot member so as to regulate the extent of angular movement transmitted from the transmitting lever to the feeding lever.

In testimony whereof I have signed my name to this specification.

LAURENCE E. TOPHAM.
